UNITED STATES PATENT OFFICE

GEORGE E. GLATTHAR, OF CLEVELAND HEIGHTS, OHIO, ASSIGNOR TO THE ART METAL COMPANY, OF CLEVELAND, OHIO, A CORPORATION OF OHIO

DESIGN FOR A LAMP

Application filed May 22, 1931. Serial No. 39,928. Term of patent 7 years.

To all whom it may concern:

Be it known that I, GEORGE E. GLATTHAR, a citizen of the United States, residing at Cleveland Heights, Cuyahoga county, Ohio, have invented a new, original, and ornamental Design for Lamps, of which the following is a specification, reference being had to the accompanying drawing, forming a part thereof.

The figure is a side elevation of a lamp showing my new design, said lamp being generally circular in form.

I claim:

The ornamental design for a lamp, as shown and described.

GEORGE E. GLATTHAR.
